UNITED STATES PATENT OFFICE.

ELIOT KEEN, OF BROOKLYN, NEW YORK.

PILOT AND NIGHT LAMP.

1,147,949.

Specification of Letters Patent. Patented July 27, 1915.

Application filed January 16, 1914. Serial No. 812,377.

To all whom it may concern:

Be it known that I, ELIOT KEEN, a citizen of the United States, and resident of the city of Brooklyn, county of Kings, State of New York, have invented a certain new and useful Improvement in Pilot and Night Lamps, of which the following is a specification.

My invention relates to incandescent electric lamps and has for its object an arrangement by means of which the position of an incandescent lamp (or controlling switch therefor) of normal candle power is indicated, when the lamp is off or substantially off and the room is dark.

A further object of my invention is to provide an arrangement by means of which when said lamp is switched off, either a night lamp of lesser candle power, or a pilot lamp is automatically lighted and vice versa.

More particularly my invention relates to a pull socket of the Hubbell type, for example, in which electrical conductors are carried down the operating chain or cord to an auxiliary electric lamp of low candle power, which terminates said chain or cord. This socket is so arranged that for one pull on the chain the lamp of normal candle power is lighted, while for another pull said lamp is extinguished and the night lamp of lesser power (or indicating lamp as the case may be) at the end of the chain is lighted instead. If desired a third pull may totally interrupt the circuit, and the device may be so arranged that a fourth pull may be utilized if desired, so that the lamp at the end of the chain may be made to emit only a dim light. Where these four pulls are used the results obtainable are as follows: One pull gives a dim illumination of the auxiliary lamp, the main lamp being non-luminous or substantially so; a second pull gives full candle power for the main lamp, the auxiliary lamp being non-luminous or substantially so; a third pull gives full candle power of the auxiliary lamp, the main lamp being non-luminous or substantially so; and the fourth interrupts the circuit so that both the main and auxiliary lamps are non-luminous.

My invention will be better understood by referring to the accompanying drawings, in which—

Figure 1 represents a preferred embodiment of my invention in side elevation, the shell of the main socket and a part of the

auxiliary socket being sectioned for the sake of clearness; Fig. 2 is a plan view of the main socket as shown in Fig. 1 with the cap removed; Fig. 3 is a section, in plan, along the line 3—3 of Fig. 1; Fig. 4 is the movable contact member of the switch; Fig. 5 is a section, in plan, taken along the line 5—5 of Fig. 1; Fig. 6 is a plan view taken from below of the ratchet member of the switch; and Figs. 7 to 10 inclusive are diagrammatic views showing the arrangement of circuits for four successive positions of the switch, Fig. 7 showing the main lamp dead and the auxiliary lamp feebly lighted, Fig. 8 showing the main lamp at normal candle power and the auxiliary lamp dead, Fig. 9 showing the main lamp dead and the auxiliary lamp fully lighted; and Fig. 10 showing the circuit totally interrupted, that is, with both the main and the auxiliary lamps dead.

In the drawings, 1 is a pull socket of substantially the Hubbell type, with some modifications which will be explained. In this socket is a main lamp 2 and a chain or cord 3 carrying at its end, an auxiliary or miniature lamp 4. A movable switch member 5, to which the upper end of chain 3 is attached, swings upon a central axis in the usual way through a small arc and carries upon its under surface a ratchet member 6 having equally spaced projecting fingers 7 adapted to engage corresponding depressions 8 in a contact member 9 arranged to rotate independently about the same center 90 as the switch member.

Spaced equally about a lower insulating disk 10 are four metallic posts 11, 12, 13 and 14 some or all of which support the upper insulating disk 15. Of these posts 14 and 12 act as stops for the movable switch member 5, the end 15¹ of said member engaging post 14 when the switch is at normal position and the notch 16 engaging post 12 when the switch is carried to its other limiting position by a pull upon the chain 3.

A resistance 17, preferably wound upon a suitable spool, rests in the top of the upper insulating member 15 just beneath the cap.

The circuits are arranged as shown in the diagrams, Figs. 7-10, one of the main conductors 18 going in the usual way to the socket shell 19 and thence, through the main lamp, to the switch center 20 and contact finger 21. Post 11 is connected to one end of the resistance 7 and the other main conductor 22 connects to the post 12. Post 13

connects to the other end of resistance 17 and to a conductor 23 which passes down through the chain 3 to the auxiliary lamp 4, while another conductor 24 from auxiliary lamp 5 4 passes through the chain and connects to conductor 22 and post 12. The two conductors 23 and 24 have each a few loose turns 25 lying free within the space between the two insulating heads.

- 10 The main and auxiliary lamps are so chosen that when in series the auxiliary lamp will give full candle power while the main lamp will only be very dimly illuminated if at all, and the resistance 7 is so 15 chosen that when it is in series with the main and auxiliary lamps, the auxiliary lamp will run at low candle power, while the main lamp, again, will be barely visible at all.
- 20 By tracing the connections in the various diagrammatic views in accordance with the above explanation, it will be seen that when the contact finger 21 is in the position of Fig. 7, the main lamp, auxiliary lamp and 25 resistance 17 will be in series. This condition is desirable where only a pilot lamp is desired for the purpose of indicating where the main lamp (or switch therefor) is located and of enabling the main lamp to be 30 turned on quickly and with certainty in the dark.

In Fig. 8 the finger has been turned to the next post 12 by one pull of the chain and the main lamp is fully on at normal candle 35 power; the auxiliary lamp is entirely cut out.

In Fig. 9 the chain has been again pulled and the contact finger moved to the next post. The main lamp and auxiliary lamp 40 are now in series and the latter, therefore, becomes a night light of full candle power so as to afford appreciable and reasonable illumination of the room without fully illuminating it, the main lamp itself being dark 45 or substantially so.

In Fig. 10 the contact finger has been advanced one step farther by another pull on the chain and now rests upon the dead post 14 and the main circuit is entirely interrupt- 50 ed so that both lamps are off.

While I have described a preferred form of socket, variations in detail may obviously be made within the spirit of my invention and the particular socket chosen has been 55 merely because I find it a convenient one.

As previously stated I may, instead of having four different switch positions, as described, giving four different arrangements of circuit used, have only three or 60 even two of said positions within the spirit of my invention.

Having described my invention, I claim:

1. The combination of a main lamp, a socket therefor, a switch within said socket, and a cord for moving said switch, an auxiliary

lamp carried by said cord, and conductors within said cord extending from the auxiliary lamp into the aforesaid socket, the main lamp only being in circuit for one position of the switch and the main lamp and auxiliary lamp being in series for another position of the switch. 70

2. The combination of a main lamp, a socket therefor, a switch within said socket, a cord for moving said switch, an auxiliary lamp carried by said cord, and conductors within said cord extending from the auxiliary lamp into the aforesaid socket, the main lamp only being in circuit for one position of the switch, the main lamp and auxiliary lamp being in series for another position of the switch, and both main and auxiliary lamps being out of circuit for a third position of the switch. 80

3. The combination of a main lamp, a socket therefor, a switch within said socket, a resistance attached to said socket, a cord for moving said switch, an auxiliary lamp carried by said cord, and conductors within said cord extending from the auxiliary lamp into the aforesaid socket, the main lamp, auxiliary lamp and resistance being in series for one position of the switch, the main lamp and auxiliary lamp only being in series for another position of the switch and the main lamp only being in circuit for a third position of the switch. 90

4. In combination, a lamp socket provided with a movable switch finger and adapted to take a main lamp, a resistance attached to said socket, a cord for moving said finger carrying an auxiliary lamp, conductors within said cord extending into said socket and adapted to be joined to the auxiliary lamp, and contact members within said socket adapted to be successively touched by the switch finger for successive pulls of the cord, the main lamp, auxiliary lamp and resistance being in series for one position of the switch finger, the main lamp and auxiliary lamp only being in series for another position of the switch finger, and the main lamp only being in circuit for a third position of the switch finger. 100

5. In combination, a lamp socket for a main lamp, a movable switch member therein, a cord having a socket for an auxiliary lamp and provided with conductors running from said socket to the main socket for moving said switch member, and electrical conductors within the socket, said switch member being arranged to control the distribution of current from a common source to the two sockets, as and for the purpose described. 110

6. The combination of a socket for a main lamp, a switch within said socket, a resistance attached to said socket, and conductors dependent from the socket carrying an auxiliary lamp at one end and mechanically at- 120 125 130

tached to the switch at the other end for moving the same, the main lamp, auxiliary lamp and resistance being in series for one position of the switch, the main lamp and auxiliary lamp only being in series for another position of the switch, and the main lamp only being in circuit for a third position of the switch.

In testimony whereof I have hereunto set my hand in the presence of two subscribing ¹⁰ witnesses.

ELIOT KEEN.
